FIRE CONTROL APPARATUS FOR GUNS

Filed Dec. 12, 1927

UNITED STATES PATENT OFFICE.

HEINRICH JUST AND HERMANN HORT, OF ESSEN, GERMANY, ASSIGNORS TO FRIED.
KRUPP AKTIENGESELLSCHAFT, OF ESSEN-ON-THE-BUHR, GERMANY.

FIRE-CONTROL APPARATUS FOR GUNS.

Application filed December 12, 1927, Serial No. 239,577, and in Germany October 27, 1926.

This invention relates to fire control apparatus for a gun having a rocking foundation which comprises a mounting on said foundation, a sighting means carrier cardanically arranged on said mounting, a gyroscope rotatable about an axis fixed on said sighting means carrier, and a body adjustable for elevation independently of the gyroscope, and the object of this invention is to so construct 0 an apparatus of the kind stated having an electrical firing device comprising two adjustable contact members adapted to register one with the other that the angular position of the axis of the gyroscope cannot be disturbed by 15 the adjusting movement imparted to said contact members. An indicating device may further be combined in a simple manner with the firing device, which indicating device gives the commander of the guns a clear image of 20 the position the gun barrels assume relative to the pointing axis arranged on the observing station, the commander thus being enabled to take suitable precautions to increase the firing speed or to eliminate disturbances 25 during the pointing operation.

An embodiment of the fire control apparatus forming the subject matter of the present invention and intended for naval guns is illustrated, by way of example, in the accompanying drawing, in which:

Figure 1 is a diagrammatic view of the apparatus, looking in the direction of the longitudinal axis of the ship, partially in section.

Figure 2 is a section on line 2—2 of Figure 1, looking from the left.

Referring to these Figures, A denotes the ship and A¹ a pedestal rigid on it and mounted at the observing station. An arcuate bearing body B is mounted to turn around a pivot b¹. This bearing body B constitutes the frame, laterally adjustable in the direction of the aim, of a sighting device. A lateral training gear with a hand wheel C is provided for bearing body B. This training gear is connected to the training gears D of the guns by an electric long-distance control device having a transmitter e' and a plurality of receivers d' corresponding to the number of guns. 50 In the drawing only a single gun is illustrated as the firing operation is the same for all the guns. The axis of curvature of the arcuate bearing body B and the axis of the pivot b' intersect in a point l, and an adjustable semi-circular member E is mounted in the

body B and adapted to be swung around said axis of curvature. A rack e' on member E and a pinion in mesh therewith and actuated by a motor F serve to effect the adjustment of member E in a vertical direction. 60

A Cardan ring G is mounted by means of two trunnions e² on member E. The axis of the trunnions passes through point l at right angles to the axis of rotation of member E. On the Cardan ring G is mounted for free 65 swing motion a casing H by means of two trunnions h¹, the common axis of which passes at right angles through the axis of the trunnions e² in the point l. A sighting telescope H² is mounted on casing H. A pointer J is 70 mounted on casing H for rotation around the axis of the trunnions h¹, which pointer may be set to the firing angle A_m corresponding to the distance of the aim relative to the sighting telescope H² by means of a small electric motor h³ mounted on casing H. The pointer J carries a mark i¹ that may register with a corresponding mark g¹ of the Cardan ring G. The mark g¹ is so located, that the axis of the Cardan ring G formed by the trunnions e², 80 representing the pointing axis of the observing station which determines the direction of the individual gun barrels, forms with the sighting line of telescope H² the firing angle A_m corresponding to the distance of the aim, 85 when the marks i¹ and g¹ register.

The marks i¹ and g¹ constitute contact pieces of an electric controlling device (not shown) for the motor F, by means of which device the motor may be so controlled automatically in a manner known in itself, that the marks i' and g' register. In the casing H is mounted a gyroscope K by means of which the sighting line of the telescope H², pointed on the aim, and the elevation of the 95 pointer J arranged on casing H may be fixed in space in vertical direction for a sufficient length of time. And due to the action of the automatic controlling device including the contact pieces i' and g' the pointing axis 100 formed by the axis of the trunnions e² is also maintained in its vertical position in space.

On the mounting L of each gun is arranged an electric motor L¹ intended to drive the elevating gear and having a device for regulating its speed, said elevating gear having a toothed arc m¹ fixed on the cradle M of the gun. A shaft N vertically mounted on the gun mounting L is in positive connection with the toothed arc m¹, which shaft serves 110

to actuate a following pointer of the receiver L^2 arranged on the gun mounting of a long distance controlling apparatus operating on the follow-the-pointer system. The receiver L^2 5 may be adjusted from the observing station to the firing angle A_m corresponding to the distance of the aim and serves together with the elevating motor L^1 , for adjusting the gun barrel in elevation. Each receiver 10 is fitted with means for allowing account being taken of a supplemental elevation due to the degree of wear of the gun barrel.

An electrical firing device, the casing L^3 of which is mounted on the gun mounting, is 15 provided for each gun. In each casing L^3 is mounted for free rotation an annular body Q carrying an adjusting mark q^1 which forms a contact piece. A pointer R is further rotatably mounted in the casing L^3 co-axially 20 with the annular body Q , which pointer is likewise fitted with a mark r^1 corresponding to mark q^1 and forming a contact piece. The contact pieces q^1 and r^1 lie in the firing circuits belonging to the individual guns and 25 having a common additional switch arranged at the commanding station common to all guns. The pointer R can be adjusted by means of a worm gearing r^2 which is so positively connected to shaft N through the intermediary of a shaft N^1 positively connected thereto and by a shafting N^3 mounted on the gun mounting and positively connected to shaft N^1 by a bevel gear n^2 , that the pointer 30 R and the gun barrel always turn in equal 35 or proportional angles. A device intended to take account of an angle of pre-ignition corresponding to the elevating speed may be interposed before the bevel gear n^2 . In this case the pointer R has imparted to it an angular position modified by the angle of pre-ignition.

An electric long distance controlling apparatus 2 is provided for each annular body Q of the firing devices of the individual guns, 45 which apparatus have a common transmitter F^1 connected to the motor F of the observing station so that an angular position corresponding to the elevation of the pointing axis arranged at the observing station (axis 50 of the trunnions e^2) can be imparted to the annular bodies Q . A device intended to take account of an angle of pre-ignition corresponding to the rolling speed of the ship may be arranged before the transmitter F^1 , 55 in which case the annular bodies Q have imparted to them an angular position altered by the angle of pre-ignition. When the marks r^1 and q^1 register, each gun has the same elevation as the pointing axis (axis of 60 the trunnions e^2) of the observing station, except for the angles of pre-ignition and a supplemental angle of elevation taken account of at the receiver L^2 .

At the common commanding station there 65 is arranged a receiver of an electric long dis-

tance controlling apparatus, the casing A^2 of which is mounted on the body of the ship. The casing A^2 has freely rotatably mounted in it an annular body Q^2 corresponding to the annular bodies Q and having an adjusting 70 mark q^3 . The front surface of the annular body Q^2 is differently colored on both sides of the diameter determined by the mark q^3 , e. g. yellow on the upper half denoted by q^4 and blue on the lower half q^5 . The annular body Q^2 is connected by a wiring 2^a to the long distance controlling apparatus F^1 , by means of which the same angular position 75 can be imparted to it as to the annular bodies Q .

The casing A^2 has rotatably mounted in it a pointer R^2 co-axial with the annular body Q^2 . Pointer R^2 corresponding to the pointer R carries an adjusting mark r^3 co-operating with the mark q^3 . The pointer R^2 can be 80 adjusted by an electric long distance controlling apparatus 3 which may be actuated selectively from transmitters S arranged on the individual guns and positively connected with the shafting N^3 , whereby the same angular position is imparted to the pointer R^2 as to the pointer R belonging to the gun in question. A wire g^3 is fixed on the front surface of the casing A^2 before the annular body Q^2 and the pointer R^2 , which wire extends 85 in the direction of a diameter that denotes the angular position of the plane of the gun platform.

When the trunnions h^1 assume horizontal position, and the sighting telescope H^2 , which 90 is automatically fixed in elevation in space by the gyroscope K , has been pointed to the aim by means of a hand wheel C of the training gear of the observing station, and the pointer J has been adjusted to the firing angle 95 A_m relative to the gyroscope casing H and to the sighting telescope H^2 by means of the motor h^3 , and the member E has been turned into such an angular position by motor F , that the marks q^1 and r^1 register, then, at any 100 inclined position of the ship's body, a gun-barrel, the axis of the bore of which coincides with the pointing axis formed by the axis of the trunnions e^2 of the observing station, 105 would be correctly pointed on the aim, that is, the pointing error, due to the canting of the gun's horizontal trunnions would be eliminated. When the marks q^1 and r^1 of the firing devices of the individual guns register, 110 all the guns have the same elevation as the pointing axis of the commanding station, except for the angle of pre-ignition and the supplemental elevation. All guns are thus 115 correctly pointed on the aim, no matter what position the ship assumes at this moment due 120 to its rolling motion. At this very moment the firing takes place, provided the additional switch arranged at the commanding station of the battery has been closed. This is true 125 in the case of "rolling through," (when the 130

gun barrels pass through the firing position merely due to the rolling motion of the ship) as well as in the case of "turning through," (when an additional motion is imparted to the gun barrels by the elevating gear L^1). In the latter case the firing of the guns takes place in the following manner: Each gun, after it has been adjusted according to the distance of the aim and the indications given by the appurtenant receiver L^2 read, reports to the commander who is attending the battery commanding station, that the gun is ready. The commander then connects the pointer R^2 of the receiver located at the battery station with the transmitter S of one of the guns ready for firing, and the pointer R^2 is adjusted to the same angular position as the pointer R of the gun in consideration, and thus forms an image of the position of the gun barrels relative to the plane of the platform of the guns by its position relative to the mark, formed by the wire a^3 , of the receiver casing A^2 . The annular body Q^2 , the angular position of which corresponds to the elevation, invariable in the space, of the pointing axis of the observing station, executes a to and fro swing motion relative to the receiver casing A^2 due to the rolling motion of the ship. The mark q^3 of body Q^2 deflects by equal angles from a middle position denoted by pointer R^2 , if the ship has a horizontal floating position, as is the rule. When the ship is rolling upward (on the side of the muzzle of the gun barrel), the pointer mark q^3 is in the range of the upper yellow half q^4 of the annular body and, when the ship is rolling downward, in the range of the lower blue half q^5 . By observing the marks r^3 and q^3 of the indicating members Q^2 and R^2 of the indicating device formed by the receiver $A^2 Q^2 R^2$, the commander is able to ascertain at any moment where the ship is in its upper or lower position. When the ship is in the upper position and the pointer mark r^3 is at its greatest angular distance from the mark q^3 within the range of the upper yellow half q^4 of body Q^2 , and the guns are to be fired while being "turned through" during the subsequent downward roll of the ship, then, after the elevating motors L^1 of all the guns have been set to the same speed and the firing circuit has been closed by throwing-in the additional switch located in the battery commanding station, the commander gives the order "Raise breech end," or he starts the elevating gears of the guns in the desired direction by operating a suitable switch of an electro-magnetic controlling device. The muzzles of the gun barrels now move with additional speed in the sense of the rolling motion, and the mark r^3 travels towards the mark q^3 with a correspondingly increased speed. As soon as these two marks register, which now takes place before the ship reaches the horizontal floating position, the marks q^1 and r^1 of the gun allotted to the receiver A^2 $Q^2 R^2$ also register, and the marks of the other guns approximately register, so that all the guns are fired approximately in a volley. Then all the guns are brought into loading position, loaded, and adjusted anew as to the distance of the aim, whereupon they are signalled as "Ready." As the shots were fired before the ship had attained the horizontal position in rolling downwards a sufficiently long time is at disposal for the carrying out of these operations during the period of time the ship takes to reach its lower position. With the upward motion of the ship, the elevating gears of the guns are started on the order "Lower breech end" in a manner corresponding to that described with the downward motion, and all shots are fired again nearly simultaneously while the gun barrels are "turned through" before the ship has reached its horizontal floating position. Thereupon the next volley is prepared at once and fired in the above-described manner after the beginning of the next downward motion of the ship. As can be seen, a sufficiently long time is at disposal with the described mode of operation, to fire two volleys during each rolling period.

When notable differences arise between the individual guns as to the required amount of supplemental elevation, so that the gun barrels in their firing positions deviate by corresponding angular amounts from the parallel position, it may happen, when small rolling angles are encountered of the same degree as these angular amounts, that upon the order "Raise breech end" or "Lower breech end" some of the guns are not fired. In this event the orders "Raise breech end" and "Lower breech end," or inversely, must be given shortly after one another; the shots lost upon the first order then are fired upon the second one.

This invention also enables redress at once, when the guns are fired while "rolling through," in case the ship has in position of rest an inclined floating position or lists over so that the marks r^1 and q^1 are unable to register upon the ship rolling. For, in this case the mark q^3 of the receiver of the commanding station does not deflect uniformly toward both sides relative to the mark r^3 . As soon as the commander observes this fact, a regulation corresponding to this angle of list is made in the receivers L^2 of all guns, so that the guns now have imparted to them an elevation modified by this angle of list and the pointers R and R^2 assume again at least approximately a middle position, from which the marks q^1 or q^3 deflect by equal angles toward both sides. The guns then can be fired when "rolling through."

What we claim and desire to secure by Letters Patent, is:-

1. A fire control apparatus for a gun

- having a rocking foundation comprising a mounting on said foundation, a sighting means carrier cardanically arranged on said mounting, a gyroscope rotatable about an axis fixed on said sighting means carrier, a member adjustable relative to said sighting means carrier for range and establishing an axis inclined with respect to the sighting line according to the firing angle, a body adjustable for elevation independently of said gyroscope according to the direction imparted to said axis relative to said mounting, an electrical firing device comprising two adjustable contact members adapted to register one with the other, connections so arranged between one of said contact members and said gun that said contact member is adjusted according to the elevation of said gun, and connections arranged between the other of said contact members and said body whereby an adjustment is imparted to said last-named contact member corresponding to the elevation of said body.
2. A device according to claim 1, in which said last-named connections comprise a long distance control apparatus.
3. A fire control apparatus according to claim 1, in which said mounting is rotatable in lateral direction and carries said body adjustable for elevation independently of said gyroscope, said sighting means carrier being cardanically mounted on said body.
4. A fire control apparatus for a gun having a rocking foundation comprising a mounting on said foundation, two adjustable index members arranged on said mounting and adapted to register one with the other, a body adjustable for elevation, means for maintaining the elevation imparted to said body in space independently of the rocking movement of said foundation, connections so arranged between one of said index members and said gun that said index member is ad-

justed according to the elevation of said gun, and connections arranged between the other of said index members and said body whereby an adjustment is imparted to said last-named index member corresponding to the elevation of said body.

5. In a fire control apparatus according to claim 4, means arranged on the mounting for said index members adapted to indicate the angular position of the foundation.

6. A fire control apparatus for a gun having a rocking foundation comprising a mounting on said foundation, a sighting means carrier cardanically arranged on said mounting, a gyroscope rotatable about an axis fixed on said sighting means carrier, a body adjustable for elevation independently of said gyroscope, an electrical firing device comprising two adjustable contact members adapted to register one with the other, two adjustable index members adapted to register one with the other, connections so arranged between one of said contact members, one of said index members and said gun that said contact and index members are adjusted according to the elevation of said gun, and connections arranged between the other of said contact and index members and said body whereby an adjustment is imparted to said last-named contact and index members corresponding to the elevation of said body.

7. In a fire control apparatus according to claim 4 for a plurality of guns means for selectively connecting each of said guns to one of said index members, the other index member being connected to said body adjustable for elevation.

The foregoing specification signed at Cologne, Germany, this 25 day of November, 1927.

HEINRICH JUST.
HERMANN HORT.
